UNITED STATES PATENT OFFICE

2,478,935

GEAR-OPERATED WRENCH

Max Moritz and Irwin MacKay, Denver, Colo., as
signors to The B. K. Sweeney Electrical Company, Denver, Colo., a corporation of Colorado

Application May 27, 1944, Serial No. 537,587

2 Claims. (Cl. 81—57)

1

This invention relates to wrenches, and particularly to wrenches for use in locations where there is restricted room.

It frequently happens that nuts or bolts on machinery are located so that it is difficult to employ conventional wrenches with sufficient force to turn them. For example, a bolt may be so located that a wrench having a handle sufficiently long to provide the adequate leverage cannot be employed because of the length of its handle; it is then difficult to apply sufficient force with a lever short enough to be used in the restricted space. Accordingly, it is an object of this invention to provide a wrench having an improved arrangement for applying adequate force to turn a machine element located in a restricted space.

Another object of the invention is to provide an improved wrench of simple and rugged construction for applying a multiplied force to a nut, bolt, or other device to be turned.

Further objects and advantages will be apparent from the following description, and the novel features of this invention will be pointed out with particularity in the claims appended to and forming a part of this specification.

For a better understanding of the invention reference may be had to the accompanying drawing in which,

Fig. 1 is a side elevation view, partly in section, of a wrench embodying the invention; and

Fig. 2 is a plan view of the wrench shown in Fig. 1.

As shown in the drawing the improved wrench comprises an elongated handle or bar 3 having a short shaft 4 journaled in an opening provided at one end of the shaft. An annular shoulder 5 is formed on the shaft and abuts the lower side of the bar 3, and a gear 6 is secured on the shaft on the opposite side of the bar. The gear may be secured rigidly to the shaft in any suitable manner, and has been illustrated as secured by a drive fit and held against rotation relative to the shaft by a key 7. The shaft is provided with a shoulder 8 to act as a stop and determine the position of the gear on the shaft so that the distance between the shoulder 5 and gear 6 is slightly greater than the thickness of the bar 3, and the shaft can, therefore, rotate freely.

The lower end of the shaft 4, as indicated at 9, is formed as a stud of square cross section so that it can be detachably secured in non-rotative engagement with standard wrench sockets one of which is shown at 10. The upper end of the shaft 4 is formed to provide a recess or

10 socket 11 of square cross section so that a standard turning bar or lever such as indicated at 12, and having a head 13 of square cross section may be employed to turn the shaft.

The wrench may thus be employed by placing the socket 10 on the device to be turned, engaging the socket with the stud 9, then holding the bar 3 stationary while applying force through the lever 12 to turn the shaft directly.

15 In many locations, however, it will be found that a lever 12 of sufficient length to turn the device engaged by the socket 10 cannot be used because of space restrictions. For such conditions a force multiplying arrangement is provided which includes a pinion 14 rotatably secured to the bar on a stud 15 and in mesh with the gear 6. The stud 15 is formed with a round head 16 and a shoulder 17 and is securely held in place by a nut 18 and lock-washer 19. The shoulder 17 insures free rotation of the pinion 14 on the bar 3 regardless of the tightening of the nut 18. The pinion is provided with a socket portion having a square socket 20 formed therein so that a lever such as the driving bar 12 may be detachably secured to drive the pinion.

20 When the pinion is rotated by the lever 12, the bar 3 being held stationary as by anchoring the same against a relatively fixed object, the force applied through the lever is multiplied because of the gear reduction ratio. Consequently a shorter lever may be employed for obtaining the same driving force as that of the longer lever necessary for direct drive of the shaft 4; the wrench may, therefore, be employed in more restricted locations. Obviously the wrench may also be employed under other circumstances requiring the application of a greater turning force; and the driving lever may be applied selectively to either of the sockets 11 and 20 according to the force required.

25 During the operation of the wrench, the bar or handle 3 not only provides the bearings for the pinion and the gear but also acts as a member of the lever system in the application of the driving force, the driving bar 12 cooperating with the bar 3 to hold the pivot of the gear 15 against rotation about the shaft 4 to provide a fulcrum and thereby transmit the multiplied driving force to the shaft. Furthermore, the fact that the shaft may be turned by application of the driving bar at a point spaced from the shaft axis makes it possible to employ this wrench in some restricted locations where the driving bar 12, regardless of its length, could not be applied directly to the shaft.

From the foregoing it is apparent that this invention provides a rugged, simple and effective wrench for applying multiplied force to a device to be turned and which is particularly useful in locations where space is restricted.

Although a single embodiment of this invention has been illustrated and described, the invention is not limited to this construction and other arrangements will occur to those skilled in the art, for example, the handle or body of the wrench need not necessarily be a straight bar; and it is intended by the appended claims to cover all modifications which fall within the spirit and scope of the invention.

What is claimed is:

1. A wrench comprising an elongated handle having an enlarged portion at one end, a circular opening through said enlarged portion adjacent the end of said handle, a shaft rotatably mounted in said opening having a collar engaging the lower surface of said enlarged portion and a shoulder spaced above said collar, a non-circular projection extending downwardly from said shaft, a first gear fixedly mounted on the upper end of said shaft having positive rotation therewith and in engagement with said shoulder, the distance between said collar and said shoulder being slightly greater than the thickness of said handle to permit free rotation of said shaft and said gear, a second gear of a different size than said first gear rotatably mounted on a stud fixed to said handle in engagement with said first gear, said stud having a cylindrical portion forming a shoulder engaging said handle to permit free rotation of said second gear, identical coupling sockets on the upper end of said shaft and on the upper end of said second gear, and a lever having a head adjacent one end for detachably engaging either one of said sockets whereby a torque applied to said lever engaged with said socket on the upper end of said shaft will produce the same torque on said projection and the same torque applied to said lever in engagement with said second gear will produce a different torque on said projection.

2. A wrench comprising an elongated handle

having an enlarged portion at one end, a circular opening through said enlarged portion adjacent the end of said handle, a shaft rotatably mounted in said opening having a collar engaging the lower surface of said enlarged portion and a shoulder spaced above said collar, a non-circular projection extending downwardly from said shaft, a first gear fixedly held by a key on the upper end of said shaft having positive rotation therewith and in engagement with said shoulder, the distance between said collar and said shoulder being slightly greater than the thickness of said handle to permit free rotation of said shaft and said gear, a pinion gear rotatably mounted on a stud fixed to said handle in engagement with said first gear, said stud having a cylindrical portion forming a shoulder engaging said handle to permit free rotation of said pinion gear, identical coupling sockets on the upper end of said shaft and on the upper end of said pinion gear, and a lever having a head adjacent one end for detachably engaging either one of said sockets whereby a torque applied to said lever engaged with said socket on the upper end of said shaft will produce the same torque on said projection and the same torque applied to said lever in engagement with said pinion gear will produce an increased torque on said projection.
